P.A.(57) **CLAIM**

The ornamental design for the catheter connector, as shown and described herein.

DESCRIPTION

FIG. 1 is a perspective view of the catheter connector in accordance with the invention;

FIG. 2 is a side elevation view thereof;

FIG. 3 is an opposite side elevation view of FIG. 2;

FIG. 4 is another side elevation view of the invention as shown in FIG. 1;

FIG. 5 is an opposite side elevation view of FIG. 4;

FIG. 6 is a top plan view of the invention; and,

FIG. 7 is a bottom plan view of the invention.

The features shown in broken lines depict environmental structure only and form no part of the claimed design.
